SPANNER WRENCH

Filed Oct. 8, 1928

INVENTOR
James G. Collins
BY Chappell & Earl
ATTORNEYS

UNITED STATES PATENT OFFICE

JAMES G. COLLINS, OF KALAMAZOO, MICHIGAN, ASSIGNOR TO ATLAS PRESS COMPANY,
OF KALAMAZOO, MICHIGAN

SPANNER WRENCH

Application filed October 8, 1928. Serial No. 310,971.

The objects of the invention are:

First, to provide a spanner wrench which is quickly and conveniently adjusted for use.

Second, to provide improved adjusting 5 jaws for such a wrench.

Third, to provide an improved adjusting slide for the jaw.

Objects pertaining to details and economies of construction and operation will definitely 10 appear from the detailed description to follow. The invention is defined in the claims.

A preferred embodiment of my invention is illustrated in the accompanying drawing, in which:

15 Fig. 1 is substantially a full size side elevation view of my improved spanner wrench, the dotted lines indicating closed position of adjustment.

Fig. 2 is an elevation view from the right 20 hand of Fig. 1, part of the handle being broken away.

Fig. 3 is a detail sectional elevation on line 3—3 of Fig. 2 showing the wrench in its closed position.

25 The parts will be identified by their numerals of reference which are the same in all the views.

1 is the wrench handle terminating in a screw driver or other suitable tool below. 2 30 is the fixed jaw slightly curved and terminating in a spanner wrench tooth 21. 22 is the engaging side pin for use as a face spanner. 3 is the movable jaw pivoted to the handle at 31 and having a laterally projecting engaging pin 32 to cooperate with the pin 22 on the fixed 35 jaw when used as a face spanner.

4 is the adjusting slide which controls the pivoted jaw. 5 is the connecting link from the slide 4 to the jaw 3 pivoted to the jaw at 40 51 and to the slide at 52. The link 5 is provided with serrations or teeth 53 at its lower end which correspond to serrations 11 on the side of the handle 1 with which they cooperate and engage when the wrench is adjusted.

45 The slide 4 is provided with a spring 41 folded upon itself and with its ends engaging the slide at each side and formed like a shoe at 42 to slide on the handle and yieldingly hold the opposing teeth in engagement. A 50 thumb screw 43 is provided centrally of the

back of the slide 4 and between the ends 42 of the spring 41 by which the jaw may be securely clamped after it has been adjusted.

The spring merely yields to facilitate adjustment of the structure which may be locked 55 during use. The structure operates fairly well without the locking screw but is made very positive when the said screw is clamped down. The operation is very clear from the description and an examination of the drawing.

I desire to claim my invention specifically as illustrated and also broadly as pointed out in the appended claims.

Having thus described my invention, what 60 I claim as new and desire to secure by Letters Patent, is:

1. In a spanner wrench, a handle terminating in a fixed jaw with suitable engaging hook, a laterally projecting engaging pin at 70 the side of the jaw, a movable jaw pivoted to the handle and having a laterally projecting engaging pin corresponding to the engaging pin on the fixed jaw, a slide on the handle consisting of a loop, a connecting link from the slide to the movable jaw whereby the same is adjusted by the adjustment 75 of the slide, teeth on the side of the handle, teeth on the end of the connecting link cooperating therewith, a spring for the slide 80 doubled on itself and its ends engaging the slide to hold the said teeth yieldingly in engagement, a set screw in said slide disposed between the recurved ends of and against the back of the said spring to lock the same in 85 place, as specified.

2. In a spanner wrench, a handle terminating in a fixed jaw, a laterally projecting engaging pin at the side of the jaw, a movable jaw pivoted to the handle and having 90 a laterally projecting engaging pin corresponding to the engaging pin on the fixed jaw, a slide on the handle consisting of a loop, a connecting link from the slide to the movable jaw whereby the same is adjusted 95 by the adjustment of the slide, teeth on the side of the handle, teeth on the end of the connecting link cooperating therewith, a spring for the slide doubled on itself and its ends engaging the slide to hold the said 100

teeth yieldingly in engagement, a set screw in said slide disposed between the recurved ends of and against the back of the said spring to lock the same in place, as specified.

- 5 3. In a spanner wrench, a handle terminating in a fixed jaw, a laterally projecting engaging pin at the side of the jaw, a movable jaw pivoted to the handle and having a laterally projecting engaging pin corresponding to the engaging pin on the fixed jaw, a slide on the handle consisting of a loop, a connecting link from the slide to the movable jaw whereby the same is adjusted by the adjustment of the slide, teeth on the 10 side of the handle, teeth on the end of the connecting link cooperating therewith, a spring for the slide doubled on itself and its ends engaging the slide to hold the said teeth yieldingly in engagement, as specified.
- 15 4. In a spanner wrench, a handle terminating in a fixed jaw, a laterally projecting engaging pin at the side of the jaw, a movable jaw pivoted to the handle and having a laterally projecting engaging pin corresponding to the engaging pin on the fixed 20 jaw, a slide on the handle consisting of a loop, a connecting link from the slide to the movable jaw whereby the same is adjusted by the adjustment of the slide, teeth on the 25 side of the handle, teeth on the end of the connecting link cooperating therewith, a set screw in said slide to lock the same in place, as specified.

30 In witness whereof I have hereunto set
35 my hand.

JAMES G. COLLINS.
